FUSE CONSTRUCTION

Hugh A. Triplett, Wilmette, Ill., assignor to
Schweitzer & Conrad, Inc., Chicago, Ill., a corporation of Delaware

Application November 17, 1939, Serial No. 304,903

12 Claims. (Cl. 200—117)

This invention relates, generally, to circuit interrupting apparatus and it has particular relation to fuse apparatus.

An object of this invention is to provide for holding an arc in a predetermined position with respect to a moving arcing chamber in a circuit interrupter.

Another object of this invention is to hold the arc in the predetermined position, as stated, and also to protect the inner surface of the circuit interrupter housing from the heat of the arc.

A still further object of this invention is to provide for holding the arc in the predetermined position, as stated, and for controlling the movement of the movable arcing chamber conjointly in accordance with two opposing forces, one being the force of the means tending to effect movement of the arcing chamber and the other being the reaction force acting in the opposite direction and caused by the arc biowout.

Other objects of this invention will, in part, be obvious, and, in part, appear hereinafter.

This invention, accordingly, is disclosed in the embodiment thereof shown in the accompanying drawing, and it comprises the features of construction, combination of elements and arrangement of parts which will be exemplified in the construction hereinafter set forth, and the scope of the application of which will be indicated in the appended claims.

For a more complete understanding of the nature and scope of this invention, reference may be had to the following detailed description taken in connection with the accompanying drawing, in which:

Figures 1A and 1B constitute a longitudinal sectional view of a concrete embodiment of the invention; and

Figure 2 is a detail sectional view taken along the line 2—2 of Figure 1A.

Referring now particularly to Figures 1A and 1B of the drawing, it will be observed that the reference character 10 designates a tubular insulating housing, preferably formed of glass, which has secured to its ends by a suitable alloy line terminals 11 and 12. It will be understood that the line terminals 11 and 12 are arranged to be mounted in fuse clips. However, it will also be understood that provision may be made for connecting the terminals 11 and 12 directly to the line conductors.

A cap 13 is threaded on to the upper end of the upper line terminal 11 and it holds in position thereon a flanged head 14 from which depends a rod-like terminal 15.

Movably mounted within the tubular insulating housing 10 is an arcing chamber, shown generally at 16, which has a bore 17 formed by sections 18 of solid insulating material such as magnesium borate, magnesium hydroxide, boric

acid, etc. The sections 18 of solid arc extinguishing material are held in place by a suitable sleeve 19 of insulating material such as fiber. It will be noted that the rod-like terminal 15 extends into and substantially fills the bore 17.

An end member 20 of suitable insulating material, such as fiber, is threaded into the upper end of the sleeve 19 and is provided with a suitable aperture through which the rod-like terminal extends. The member 20 is provided with a transverse slot 21 with which a pin 22, extending transversely through the rod-like terminal 15, interfits to prevent relative rotary movement between the movable arcing chamber 16 and the rod-like terminal 15.

A ring-like clamp nut 23 is threaded onto the end member 20 and provides a flange against which one end of a coil compression spring 24 can react. The other end of the spring 24 reacts against the under side of the flanged head 14, as illustrated.

At its lower end the arcing chamber 16 is provided with an end member 25, preferably formed of fiber, which is held in place by a retaining member 26 which, in turn, is threaded on to the lower end of the sleeve 19. The retainer member 26 is provided with a shoulder 27 which is arranged to abut a shoulder 28 extending inwardly from the lower line terminal 12 for the purpose of limiting the downward movement of the arcing chamber 16 under the influence of the compression spring 24, so that it does not uncover the lower arcing end of the rod-like terminal 15.

As shown more clearly in Figure 2 of the drawing, the retainer member 26 is provided with an integrally formed bridge 29 having a suitable centrally located aperture through which the threaded shank 30 of a terminal 31 extends. A nut 32 is threaded on to the shank 30 and securely holds the terminal 31 in a position which is substantially in axial alignment with the rod-like terminal 15. Strain and fusible elements 33 and 34 are provided for interconnecting the rod-like terminal 15 and the arcing terminal 31. It will be observed that the lower end 35 of the rod-like terminal 15 is deformed onto the strain and fusible elements 33 and 34 and that the upper end 36 of the arcing terminal 31 is likewise deformed onto the other end of these elements. It will be understood that the strain element 33 comprises a relatively high strength wire, such as nickel chromium alloy wire, and that the fuse shown at 34 is formed preferably of a silver wire.

A terminal 38, having a shank 39 threaded into the lower end of the nut 32, has a portion 40 that is deformed onto a pair of flexible conductors 41 which are long enough to extend out of the lower end of the tubular insulating housing 10. The lower ends of the flexible conductors 41

are disposed in suitable slots 42 in the lower end of the lower line terminal 12 and are held or clamped in position securely by a flange 43 of a clamp nut 44, the lower portion 45 of which forms a basket or a catching device for receiving the flexible conductors 41 and insuring that they are not expelled beyond the limits shown by the broken lines. The basket or catching device 45 is provided with suitable apertures 46 which readily permit the outward flow of the arc blast.

It is desirable that the inner surface of the tubular insulating housing 10, which as indicated is preferably formed of glass, be protected from the heat of the arc that is formed between the rod-like terminal 15 and the arcing terminal 31. For this purpose a metallic arc chute or shield 47 is threaded, as shown, onto the lower end of the retainer member 26 and interposes a suitable barrier between the arc that is drawn and the inner surface of the tubular insulating housing 10. It will be noted that the shield or arc chute 47 is relatively short as compared to the distance between the arcing terminal 31 and the lower end of the tubular insulating housing 10. Such a construction can be employed since the arcing terminal 31 is securely fastened to the lower end of the movable arcing chamber 16 and is not expellable relative thereto by any pressure that may be generated by the arc blast.

It will be observed that the lower end of the bore 17 and the continuation thereof in the member 25 is flared outwardly to provide a reaction area against which the pressure generated by the arc extinguishing medium that is evolved from the arc extinguishing material can react in a direction which is opposite to the direction in which the arcing chamber 16 is biased by the coil compression spring 24. It is desirable to provide this differential action so that the movement of the arcing chamber 16 can be conjointly controlled in accordance with the biasing force of the spring 24 acting in one direction and the force acting on the reaction area provided by the flared-out portion 48 acting in the opposite direction, so that the amount of arc extinguishing material that is exposed to the heat of the arc will vary inversely with its magnitude. When such a differential action is not employed and a large quantity of arc extinguishing material is exposed to the heat of a relatively heavy fault current arc, a large quantity of arc extinguishing medium is evolved which, in many instances, creates such tremendous pressure that the circuit interrupter is literally blown to pieces. The amount of arc extinguishing medium that is evolved under such circumstances is considerably in excess of that which can be efficiently employed for arc extinguishing purposes. Since the reaction force of the arc extinguishing medium on the reaction area provided by the flared-out portion 48 will vary directly as the magnitude of the arc current, then the movement of the arcing chamber 16 downwardly under the influence of the coil compression spring 24 will vary inversely with the magnitude of the arc current and, consequently, a relatively small amount of the arc extinguishing material will be subjected to the heat of the arc under these circumstances.

It will be obvious that this reaction effect can be varied somewhat by changing the area of the bridge 29 of the retainer member 26. By decreasing this area the effect of the reaction force is increased and vice versa.

Since certain other changes can be made in the above construction and different embodiments of

the invention can be made without departing from the scope thereof, it is intended that all matter contained in the foregoing description or shown in the accompanying drawing shall be interpreted as illustrative and not in a limiting sense.

What is claimed as new is:

1. In a circuit interrupter, in combination, a pair of line terminals in insulated spaced relation, 10 a rod-like terminal extending from one of said line terminals, an arcing chamber biased for movement relative to said rod-like terminal, an arcing terminal fastened to said arcing chamber and movable therewith between which and said rod-like terminal an arc is adapted to be formed, means for releasing said arcing chamber for said movement, stop means limiting movement of said arcing chamber such that it does not uncover the arcing end of said rod-like terminal, and flexible conductor means interconnecting said arcing terminals and the other line terminal.
2. In a circuit interrupter, in combination, a rod-like terminal, an arcing chamber telescoped with and biased for movement relative to said rod-like terminal, an arcing terminal fastened to said arcing chamber and movable therewith between which and said rod-like terminal an arc is adapted to be formed, means for releasing said arcing chamber for said movement, and stop means limiting movement of said arcing chamber such that it does not uncover the arcing end of said rod-like terminal.
3. In a circuit interrupter, in combination, a tubular arcing chamber having a longitudinal bore, a rod-like terminal filling said bore, means biasing said arcing chamber for movement along said rod-like terminal, an arcing terminal fastened to said arcing chamber and movable therewith and between which and said rod-like terminal an arc is adapted to be formed substantially axially of the latter, means for releasing said arcing chamber for said movement, and stop means limiting movement of said arcing chamber such that it does not uncover the arcing end of said rod-like terminal.
4. In a circuit interrupter, in combination, a pair of line terminals in insulated spaced relation, a rod-like terminal extending from one of said line terminals, a tubular arcing chamber having its bore formed by material capable of evolving an arc extinguishing medium due to the heat of an arc, said tubular arcing chamber being telescoped with said rod-like terminal from one end and biased for movement with respect thereto and having a reaction area at the other end, an arcing terminal fastened to said arcing chamber and movable therewith between which and said rod-like terminal an arc is adapted to be formed, means for releasing said arcing chamber for said movement which is controlled by two opposing forces, one being the force biasing said arcing chamber for movement along said rod-like terminal and the other being the reaction force of the arc extinguishing medium on said reaction area, and flexible conductor means interconnecting said arcing terminal and the other line terminal.

5. In a circuit interrupter, in combination, a rod-like terminal, a tubular arcing chamber having its bore formed by material capable of evolving an arc extinguishing medium due to the heat of an arc, said tubular arcing chamber being telescoped with said rod-like terminal from one end and biased for movement with respect thereto and having a reaction area at the other end, and an

arcing terminal fastened to said arcing chamber and movable therewith between which and said rod-like terminal an arc is adapted to be formed, means for releasing said arcing chamber for said movement which is controlled by two opposing forces, one being the force biasing said arcing chamber for movement along said rod-like terminal and the other being the reaction force of the arc extinguishing medium on said reaction area.

6. In a circuit interrupter, in combination, a tubular arcing chamber having its bore formed by material capable of evolving an arc extinguishing medium due to the heat of an arc and having a reaction area at one end, a rod-like terminal filling said bore from the other end, means biasing said arcing chamber for movement along said rod-like terminal, and an arcing terminal fastened to said arcing chamber and movable therewith and between which and said rod-like terminal an arc is adapted to be formed substantially axially of the latter, means for releasing said arcing chamber for said movement which is controlled conjointly by the force of said biasing means acting in one direction and the reaction force of the arc extinguishing medium on said reaction area acting in the opposite direction.

7. In a circuit interrupter, in combination, a tubular housing of insulating material having line terminals at its ends, a rod-like terminal extending from one of said line terminals inwardly of said housing, an arcing chamber biased for movement relative to said rod-like terminal, an arcing terminal fastened to said arcing chamber and movable therewith between which and said rod-like terminal an arc is adapted to be formed, means for releasing said arcing chamber for said movement, a shield carried by said arcing chamber on the end thereof toward which it moves for protecting the inner surface of said housing from the heat of the arc, and flexible conductor means interconnecting said arcing terminal and the other line terminal.

8. In a circuit interrupter, in combination, a tubular housing of insulating material having line terminals at its ends, a rod-like terminal extending from one of said line terminals inwardly of said housing, an arcing chamber biased for movement relative to said rod-like terminal, an arcing terminal fastened to said arcing chamber and movable therewith between which and said rod-like terminal an arc is adapted to be formed, means for releasing said arcing chamber for said movement, a metallic shield carried by said arcing chamber for protecting the inner surface of said housing from the heat of the arc, said shield being relatively short as compared to the distance between said arcing terminal and the other line terminal, and flexible conductor means interconnecting said arcing terminal and said other line terminal.

9. In a circuit interrupter, in combination, a tubular housing of insulating material having line terminals at its ends, a rod-like terminal extending from one of said line terminals inwardly of said housing, a tubular arcing chamber having its bore formed by material capable of evolving an arc extinguishing medium due to the heat of an arc, said tubular arcing chamber being telescoped with said rod-like terminal from one end and biased for movement with respect thereto and having a reaction area at the other end, an

arcing terminal fastened to said arcing chamber and movable therewith between which and said rod-like terminal an arc is adapted to be formed, means for releasing said arcing chamber for said movement which is controlled by two opposing forces, one being the force biasing said arcing chamber for movement along said rod-like terminal and the other being the reaction force of the arc extinguishing medium on said reaction area, a shield carried by said arcing chamber for protecting the inner surface of said housing from the heat of the arc, and flexible conductor means interconnecting said arcing terminal and the other line terminal.

10. In a circuit interrupter, in combination, a tubular housing of insulating material having line terminals at its ends, a rod-like terminal extending from one of said line terminals inwardly of said housing, a tubular arcing chamber having its bore formed by material capable of evolving an arc extinguishing medium due to the heat of an arc, said tubular arcing chamber being telescoped with said rod-like terminal from one end and biased for movement with respect thereto and having a reaction area at the other end, an arcing terminal fastened to said arcing chamber and movable therewith and connected thereto by fusible means upon blowing of which an arc is adapted to be formed whereupon said arcing chamber is released for said movement which is controlled by two opposing forces, one being the force biasing said arcing chamber for movement along said rod-like terminal and the other being the reaction force of the arc extinguishing medium on said reaction area, a shield carried by said arcing chamber for protecting the inner surface of said housing from the heat of the arc, and flexible conductor means interconnecting said arcing terminal and the other line terminal.

11. In a circuit interrupter, in combination, a pair of line terminals in insulated spaced relation, a stationary terminal extending from one of said line terminals, an arcing chamber biased for movement relative to said stationary terminal, a movable terminal connected to said stationary terminal by fusible means, flexible conductor means interconnecting said movable terminal and the other line terminal, said arcing chamber being released for movement on blowing of said fusible means, stop means limiting movement of said arcing chamber such that it does not uncover the arcing end of said stationary terminal, and a catching device arranged and adapted to receive said flexible conductor means on blowing of said fusible means.

12. In a circuit interrupter, in combination, a tubular insulating housing, a terminal at each end of said housing, a rod-like terminal fastened to one end terminal and extending into said housing, an arcing chamber telescoping with said rod-like terminal and movable relative thereto toward the other end terminal, a movable terminal connected to said stationary terminal by fusible means, flexible conductor means connecting said movable terminal and said other end terminal, stop means limiting movement of said arcing chamber such that it does not uncover the arcing end of said rod-like terminal, and catching means at the end of said housing where said other end terminal is located for receiving said flexible conductor means when said fusible means blows.

HUGH A. TRIPLETT.
